UNITED STATES PATENT OFFICE.

CONRAD KOHLER, OF ZURICH, SWITZERLAND.

DEVICE FOR THE RECUPERATION OF AVAILABLE HEAT ON STEAM-LOCOMOTIVES PROVIDED WITH SURFACE CONDENSERS.

1,342,544.

Specification of Letters Patent.

Patented June 8, 1920.

Application filed September 25, 1919. Serial No. 326,338.

To all whom it may concern:

Be it known that I, CONRAD KOHLER, a citizen of the Republic of Switzerland, residing at Hardturmstrasse 19, Zurich, Switzerland, have invented certain new and useful Improvements in Devices for the Recuperation of Available Heat on Steam-Lo-
comotives Provided with Surface Condensers; and I do hereby declare the following
10 to be a clear, full, and exact description of the invention, such as will enable others skilled in the art to which it appertains to make and use the same, reference being had to the accompanying drawing, and to letters
15 or figures of reference marked thereon, which form a part of this specification.

This invention relates to a device for the recuperation of available heat on a steam locomotive provided with a surface con-
20 denser. According to this invention the con-
densed steam discharged by the surface con-
denser is forced at first through a recuperator or feed heater heated by the exhaust steam of auxiliary machines of the locomo-
25 tive and then through a recuperator or feed heater heated by the flue or combustion gases of the boiler and is finally pumped into the
boiler.

At the present time electric locomotives
30 are introduced more and more in the rail-
way traffic because it is found that the work-
ing with electric locomotives is, at least in
countries where water powers are available
35 and coal is expensive, more economical than
the working with steam driven locomotives.
Electric locomotives are however dependent
on at least one central power plant. Conse-
quently, all locomotives are stopped when
40 the central power plant or the intermediate
conduits fail to deliver power. Owing to
this, it is still preferred, particularly also
for military reasons, not to centralize the
delivery of the power required for the work-
45 ing of railways and to drive each single
locomotive independently of the other ones.
This is only possible, however, when using
steam locomotives. It is therefore the task
of the railway engineers to design steam lo-
50 comotives working in a more economical
manner and to take advantage in the best
possible way of any available energy of heat.
This task is fulfilled by a device designed
according to the present invention.

The accompanying drawing illustrates by
55 way of example a diagrammatic side view of

a locomotive driven by a steam turbine and provided with a surface condenser.

1 designates the main steam turbine driv-
ing the locomotive. The exhaust steam of
this turbine 1 is discharged through the con-
necting pipe 2 into the surface condenser 3.
The water of condensation or condensed
steam collecting on the bottom of this con-
denser 3 is drawn through a pipe 4 covered
with non-conducting material by a pump 6
driven by an auxiliary turbine 5 and it is
then discharged through a pipe 7, also cov-
ered with non-conducting material, into a
recuperator or feed heater 8. The latter is
heated by the exhaust steam of the auxiliary
turbines 5 and 10, which drive the pumps 6,
6' and the fan 9 respectively, the exhaust
steam being supplied to said feed heater 8
through the pipe 11. The water of con-
densation heated in the recuperator 8 to a
higher temperature could now be fed into an
intermediate tank or reservoir 15 connected
to the boiler feed pump. In order to heat
however said water of condensation to a still
higher temperature, it is fed from the re-
cuperator 8 through the pipe 12 covered
with non-conducting material into a second
recuperator or feed heater 13 which is heat-
ed by the flue or combustion gases of the
boiler 14 of the locomotive. It is only from
this second recuperator or feed heater 13
85 that the water of condensation or the con-
densed steam is supplied through the pipe
16 into the intermediate tank 15 connected
to the boiler feed pump by means of the pipe
17. The pipes 16 and 17 are also covered
90 with non-conducting material. When the
water of condensation discharged from the
surface condenser 3 has for instance a tem-
perature of 50° C., it can be heated in the
first feed heater or recuperator 8 up to
95 80°-90° C. and in the second feed heater
or recuperator 13 up to 130° C., so that it
contains a much greater quantity of heat
energy than in the case in which it would be
100 directly used after leaving the surface con-
denser 3 for feeding the boiler of the loco-
motive. When required, additional water
can be supplied to the condensed steam con-
tained in the intermediate tank 15.

105 I claim:

1. In a locomotive driven by a steam-
power engine and provided with a surface
condensing plant, which plant comprises
auxiliary machines driven by steam-power 110

- engines and means for reconveying the condensed steam into the boiler of the locomotive, a device for heating the condensed steam that has to be conducted from the surface condenser back into the boiler, said device comprising a feed heater heated by the exhaust steam of said auxiliary machines, a feed heater heated by the combustion gases of the boiler, and means for conducting the condensed steam successively through said two feed heaters.
2. In a locomotive driven by a steam-power engine and provided with a surface condensing plant, which plant comprises auxiliary machines driven by steam-power engines and means for reconveying the condensed steam into the boiler of the locomotive, a device for heating the condensed steam that has to be conducted from the surface condenser back into the boiler, said device comprising a first feed heater heated by the exhaust steam of said auxiliary machines, and a second feed heater heated by the combustion gases of the boiler, said second feed heater being arranged in series with the first feed heater.

3. In a locomotive driven by a steam-power engine and provided with a surface condensing plant, which plant comprises auxiliary machines driven by the steam-power engines and means for reconveying the condensed steam into the boiler of the locomotive, a device for heating the condensed steam that has to be conducted from the surface condenser back into the boiler, said device comprising a feed heater heated by the exhaust steam of said auxiliary machines, a feed heater heated by the combustion gases of the boiler, means permitting the condensed steam to pass successively through said two feed heaters, and an intermediate tank arranged behind said two feed heaters and from which the heated condensed steam is drawn out by the pump forcing it into the boiler.

In testimony that I claim the foregoing as my invention I have signed my name.

CONRAD KOHLER.
